UNITED STATES PATENT OFFICE.

WILLIAM H. TAYLOR, OF ROOD, FLORIDA.

CRATE.

Application filed April 26, 1924. Serial No. 708,164.

To all whom it may concern:

Be it known that I, WILLIAM H. TAYLOR, a citizen of the United States, residing at Rood, in the county of Palm Beach and State of Florida, have invented certain new and useful Improvements in Crates, of which the following is a specification.

This invention relates to crates and the object thereof is to provide a crate composed of separable parts which may be folded into a compact bundle when the crate is not in use.

A further object thereof is to provide a crate simple in construction, composed of few parts, and yet strong and durable in use.

A still further object thereof is to provide a crate of the character described embodying novel fastening means for the several parts thereof.

Other objects and advantages will become apparent during the course of the following specification.

In the drawings:—

25 Figure 1 is a side elevational view of a crate constructed in accordance with my invention;

Figure 2 is an end elevational view thereof;

30 Figure 3 is a detail plan view of one of the end members thereof;

Figure 4 is a detail perspective view of a fastening element used in connection with my invention;

35 Figure 5 is a detail plan view of the slat members of my crate;

Figure 6 is a detail view of bail securing element used in connection with my invention;

40 Figure 7 is a detail perspective view of a bail used in connection with my invention;

Figure 8 is a top plan view of a modified form of my invention;

45 Figure 9 is a side elevational view thereof; and,

Figure 10 is a detail sectional view of a still further modified form of my invention.

Referring now to the several figures of the drawings in which like numerals indicate like parts throughout, the numeral 1 indicates my crate generally the same being formed of end members 2 and 3 having double pointed fastening elements and tacks

55 4, as shown clearly in Figures 3 and 4, at

spaced intervals around the periphery thereof. I further provide a flexible member 5 formed of a series of spaced slats 6 suitably secured as indicated at 7 to bails 8 having their ends turned to form heads 9 for a purpose to be presently described. The upstanding points 10 of the fastening elements 4 are adapted to engage and penetrate the ends of the slats 7 when the flexible element 5 is placed around the end members 2 and 3 to form the crate and the portion 11 of the flexible element 5 at such times constitutes a hinged top whereby the contents of the crate may be removed without completely removing the slats from the end members. 60 The top 11 may be securely fastened for shipping or the like by inserting through the adjacent heads 9 of the bails 6 a rod 12 or other suitable fastening member formed of twisted wire having a head 13 and the 65 loose lower ends 14 and 15 of which are passed through and wrapped around the heads 9 of the bail 8 thereby securing the rod 12 in position and preventing the removal of the flexible element 5 from the 70 end members 2 and 3. In order to make the slats more secure and prevent side slip or the like, I employ in connection with the end members 2 and 3, a plurality of securing bails 16 twisted to form an eye 17 in 75 the central portion thereof and having the ends bent to form eyes 18 which are adapted to engage the adjacent bail 8 the eye 17 being slipped over the head 19 of a securing element formed of twisted wire or the like 80 and arranged in an opening 21 arranged centrally of the end members 2 and 3 and having its free ends 22 bent to retain said securing elements therein. A pin or wire 23 may be slipped through the head 19 to prevent the securing bails slipping or being improperly removed.

In Figures 8 and 9 is shown a crate having circular end members 2 and 3 and constructed in accordance with my invention as 100 described with the exception that, in this form of my invention I employ rigid rod 12^a and should the slats 6 be arranged to abut one another as shown in the detail sectional view, a slot 24 is cut at the adjoining 105 ends of the slats in which the rod 12 may be carried in order to protect the same and that the exterior of the crate will present no projections.

Having described my invention, what I 110

claim as new and desire to secure by Letters Patent, is:—

- 5 1. A crate of the character described, embodying end members, pointed securing members arranged around the periphery thereof, a flexible slatted element adapted to be secured around said end members and be engaged by said pointed securing members.
- 10 2. A crate of the character described, embodying end members, pointed securing elements arranged around the periphery thereof, a flexible element formed of spaced slats secured to bails and adapted to be secured around said end members and be engaged by said pointed securing members.
- 15 3. A crate of the character described embodying end members, pointed securing elements arranged around the periphery thereof, a flexible element formed of spaced slats secured to bails having heads at either ends thereof, said element being adapted to be passed around the end members and be engaged by said pointed securing members,
- 20 25 4. A crate of the character described, embodying end members, pointed securing elements arranged around the periphery thereof, a flexible element formed of spaced slats secured to bails having heads at either ends thereof, said element being adapted to be passed around the end members and be engaged by said pointed securing members,
- 30 25 45 50 55 5. A crate of the character described, embodying end members, pointed securing elements carried thereby, spaced slats secured to bails, heads formed on the opposite ends of said bails, a securing element for said bails, a plurality of bail ties detachably carried by the end members and adapted to engage the nearest bail.
6. A crate of the character described, embodying end members, pointed securing elements carried thereby, spaced slats secured to a plurality of bails, heads formed on the opposite ends of the bails, a securing element adapted to be passed through the heads of the bails, a plurality of bail ties bent to form eyes midway thereof, said eyes being receivable on an element carried centrally of the ends, eyes formed on the free ends of said ties and adapted to engage the nearest bail.

In testimony whereof I affix my signature in the presence of two witnesses.

WILLIAM H. TAYLOR.
